UNITED STATES PATENT OFFICE

ISAAC C. DECKER, OF MONTGOMERY, PENNSYLVANIA

METHOD AND APPARATUS FOR UPHOLSTERING FURNITURE

Application filed February 17, 1928. Serial No. 255,133.

This invention pertains to an improved method of and apparatus for upholstering furniture.

The invention has for its main object the provision of means whereby furniture of the so-called over-stuffed type may be expeditiously produced while at the same time effecting a body form and a finish superior to that which obtains where hand work alone is employed.

In the production of over-stuffed furniture there is commonly employed, between the frame of the article and the outer finish fabric, layers of various stuffing materials, or several layers or thicknesses of the same material, over which the finish fabric is closely drawn to partially compact the same and to give to the article its desired outline and contour. The placement of the stuffing or filling upon the frame work and the placement of the finish fabric over such filling, the drawing of the same to place over the filling and the securing of the fabric to the frame requires considerable skill and training in order to produce that smooth and even finish which is essential to a high grade piece of furniture.

The manual operation is of necessity time consuming and subject to variation in the results produced; hence pieces of the same suite will vary in contour and outline or, in other words, will not fully match up throughout.

Under my method and with the apparatus hereinafter set forth any number of like units, say for instance over-stuffed arm chairs, may be quickly upholstered and to all intents and purposes will be substantial duplicates.

While the invention is shown and herein-after described in connection with a chair it is to be understood that the method lends itself to the production of other articles of furniture as well as elements thereof.

In the annexed drawings I have illustrated the invention in connection with two forms of mechanisms, one for the production of the arms of a chair, and the other for the production of the arms and likewise the over-stuffed back.

In said drawings,
50 Figure 1 is a perspective view of the press

adapted to form the two arms of a chair, the overlying member for exerting downward pressure upon the chair frame being omitted,

Figure 2 a similar view showing the covering or finish fabric in place and at the right the filling or stuffing overlying the same, 55

Figure 3 an end elevation with a chair frame in an inverted position ready to be forced downwardly, the frame and portions of the mechanism being shown in section, 60

Figure 4 a like view with the chair frame forced downwardly, the filling compressed and the finished fabric tensioned. Said view at the left shows the fabric brought to its final position and at the right it is shown in section, 65

Figure 5 is a perspective view of a press of the type above illustrated combined with a back contouring and forming element,

Figure 6 a similar view as seen from the opposite side, the parts in both of the figures being shown in their final pressing position, 70

Figure 7 a longitudinal vertical sectional view showing the back forming element and the movable arm pressing member in their retracted position, and 75

Figure 8 a similar view with such parts moved to their final forming or pressing position.

Referring first to the construction shown in Figures 1 to 4 inclusive, 1 denotes a suitable stand or table on the top 2 whereof are mounted two trough-shaped elements each having associated therewith a presser plate adapted to compress the inner vertical portion of the filling. Inasmuch as these parts are duplicated in the structure illustrated one side or set only will be described and like parts of the opposite set will be similarly numbered with the exponent "a" added thereto. It will be understood of course that where but a single element such as a single arm or back is to be formed only a single unit or mechanism will be employed. 80

Secured upon the top 2 is a base or support 3 having a longitudinally extending trough or concave mold 4 secured thereto. Said trough is preferably formed from sheet metal and is secured fixedly in place except at its inner edge where, as indicated at 5, it is free 85

and extends upwardly above the base and in overlapping relation to the lower edge of the side compression member 6. As will be seen the mold is open at each end and the two molds 4 and 4^a are set in slightly converging relation to conform to the angularity desired to be given to the finished chair arms from the back to the front.

Hingedly connected to the inner portion of base 3 and extending lengthwise thereof is the presser plate or member 6 and having that face which is next to the mold or trough 4 given that contour which it is desired to impart to the inner side of the chair arm. In the instant case the presser plate is provided with a wedge-shaped block or filler piece 7 which when the parts are brought into pressing relation will effect the desired contour of the finish fabric by compression of the underlying filling.

The base 3 will be provided with a series of pins 8 along its upper face outward of the trough 4 and likewise with pins 9 at each end below the trough. Pins 10 will also be provided in the ends of the presser plates 6.

Presser plate 6, where both arms are to be formed at the same time, is interconnected with the presser plate 6^a through a pair of interconnected arms or levers 11 and 12, said levers being hinged at their outer ends to the respective plates 6 and 6^a and to each other at their inner ends. With the parts in the position shown in Figure 1, in which the presser plates 6 and 6^a are retracted, the levers 11 and 12, which in effect form a toggle, abut at their adjacent ends upon a stop block 13 secured to the member 2. This block arrests the further downward movement of the levers 11 and 12, at which time the weight of the arms 11 and 12 holds the presser plates impotively in retracted position.

With the parts in the position shown in Figure 1 the operator will first place the arm covering or goods denoted by 14, Figure 2, in position over the trough empaling it as indicated upon the pins 8, 9 and 10. The free end is drawn inwardly over the presser plate 6 while the stretcher cloth 15, which is attached to the inner end of the cover 14, takes the position shown in Figure 2.

In empaling the cloth or covering 14 the operator will take care that it does not contact the trough but stands away therefrom as indicated in Figure 3. He will then place the filling over the cloth as indicated at the right in Figure 2. This filling may be of any approved form but preferably there is first imposed upon the cloth a layer of cotton batting 16 and immediately over the trough and upwardly adjacent the presser plate 6^a a second cheaper filling denoted by 17. This is, of course, done upon both sides where two arms are to be simultaneously formed upon the chair frame. The chair frame is shown in Figures 3 and 4 and is of the usual form

and embodies, among others, the upper arm elements 18, and the intermediate and side braces 19 and 20, respectively.

Attached to the upper elements 18 and 18^a are springs 21 but said springs need not be present and in fact will not be present where certain furniture elements are being produced under the present method.

When a chair frame is placed upon the apparatus the parts come to the position shown in Figure 3, the fabric 14 being slightly stretched by the weight of the imposed chair frame.

A plunger or platen 22 is then moved downwardly against the chair frame and pressure is applied through any suitable means (not shown). Prior to this, however, the operator will preferably slightly inturn the edges of the cotton batting 16, see Figure 3, so that when the platen 22 is fully lowered the edges of the batting will roll inwardly as the frame moves downwardly. At the same time the finish covering 14 will be stretched and drawn taut over the filling and the presser plates through such drawing action will be swung outwardly or away from each other to the position shown in Figure 4 where they will be held by straightening of the levers or links 11 and 12.

The downward movement of the chair frame and the inward movement of the plates compresses the filling and at the same time places the finish cloth 14 under tension as the latter is held during such operation by the various empaling pins.

It is to be noted that the presser plates begin to move to pressing position as the chair frame is moved downwardly but they stand away sufficiently from the chair frame during such period as to prevent a dragging effect being exerted upon the filling.

With the pressure still exerted and the covering clamped in the troughs or forms the operator draws the stretcher cloth 15 outwardly over the intermediate brace 19 and tacks it to the outer face of brace 20 and 20^a as the case may be. He then draws the edges of the finish cloth 14 from the pins and tacks the same to the various frame elements, or these steps may be reversed, after which front finish panels as 23, shown in part at the left of Figure 4, may be positioned to cover the edges at this point. Outside side finish fabric (not shown) will also be positioned and tacked in place but as these finish steps are well known and have no direct bearing upon this invention full exposition thereof is not deemed essential.

The platen 22 is then raised, the links 11 and 12 broken from their straightened position to retract the presser plates 6 and 6^a after which the chair is lifted off of the machine.

Not only does the machine form and contour the arms but it has been found in actual practice that by having the chair in an in-

verted position no difficulty is experienced in maintaining the filling or stuffing in place and it likewise enables the operator to more expeditiously handle the stretcher strips 15 and tack the same in place.

5 In Figures 5 to 7 inclusive the same general arrangement of arm contouring means is illustrated combined with a back contouring device.

10 In this showing the trough elements are shown as having a slightly different contour and the filler strips 7 are omitted; the parts are therefore numbered as in the above description.

15 As will be seen upon reference to Figures 7 and 8 the frame of the machine is provided with a cross bar 24 formed with a groove in its upper face to receive the rounded lower end of a back contouring and compression member designated generally by 25. This arrangement allows the compression member to be rocked and for the purpose of effecting such movement a toggle comprising links 26 and 27 is interposed between a 20 fixed portion of the machine and a bracket 28 attached to said member 25. A hand lever 29 connected to the toggle by a rod 30 is provided for actuating the toggle and as a consequence rocking the compressor plate.

30 On its outer face adjacent its lower end the plate is provided with a trough-shaped member or element 31 curved or contoured to conform with the top of the back of the chair which is to be upholstered. A series of pins

35 32 extend outwardly from the plate below the trough to which the cover goods for the forward face of the back is attached, the goods being carried over the trough, upwardly along the plate and over the upper end thereof. Such goods may have stretcher strips attached to its sides as is usual.

40 As will be best seen upon reference to Figure 5 the upper part of the plate 25 is materially narrower than the lower portion which carries the back top conforming trough 31 or is of a width somewhat less than the distance between the arm compression plates 6 and 6^a.

45 Extending outwardly from each of the side edges of plate 25, at the upper narrow portion thereof and at right angles to the face of the plate, is a blade or wing denoted respectively by 33 and 33^a. Said blades are preferably formed from rigid sheet metal plate and the lower edges thereof are rounded as 50 shown in Figures 7 and 8.

55 Assuming that the form of press just set forth is to be employed the operator will position the covering elements and place the stuffing thereon, the stuffing for the back ex-

60 tending up from trough 31 and resting on the fabric overlying the back compression plate.

With the parts in the position shown in Figure 7 a chair frame having the back springs secured to the back frame will be 65 placed in an inverted position, as before, on

the press and forced downwardly. The arms will of course be contoured as above set forth and in addition the upper curved and rounded edge of the back will be likewise contoured by the trough 31. Lever 29 is then 70 depressed straightening the toggle and thereby rocking the back compression plate forcing the covering goods and filling firmly and smoothly against the back springs. At the same time wings 33 and 33^a will carry the 75 stretcher strips attached to the back covering between the usual upholstering strips of the chair frame and to the rear of the frame where they may be readily tacked. So too, they will carry the stretcher strips at the ends 80 of the arm coverings or the ends of said coverings through in a like manner. This obviates the necessity of the use of the usual "stuffing stick" commonly employed, along with its attendant disadvantages. Again, the 85 wings separate the filling between the arms and the back when the operator is positioning the same.

The back contouring element in the structure, as above described, is designed primarily for forming backs, the upper portion of which are intended to be completed by an imposed wooden finishing element. It may be used, however, for forming strictly over-stuffed backs as well.

90 As will be appreciated by those skilled in the art the machine in both of its described forms makes for better and more expeditious work than can possibly be done under old hand methods now commonly in use.

95 It is to be understood that generically considered the principle involved in the present invention may be employed for forming and contouring furniture elements other than arms and backs and the broader claims are 100 to be so construed.

105 What is claimed is:

110 1. That method of contouring and covering over-stuffed furniture elements which consists in securing the covering adjacent its edges over a form and in spaced relation thereto; placing stuffing on said covering; forcing the furniture element against the stuffing and thereby compressing the stuffing at the initial zone of contact and thereby tensioning the covering and carrying it into contact with the form; causing the tension of the cover to produce a compressive action between the stuffing and another face of the furniture element other than that which first 115 contacts the stuffing; securing the covering to the furniture element while the covering is held; and finally removing the covered furniture element from the form.

120 2. In an apparatus for producing over-stuffed furniture, the combination of a form contoured to the desired shape of the upper portion of a furniture element to be covered; a presser plate hinged adjacent one side of the form; and means for securing a covering 125

fabric along the outer edge of the form, the ends thereof and the ends of the presser plate.

3. In an apparatus for producing over-stuffed furniture, the combination of a form contoured to the desired shape of the upper portion of the arm of a chair to be covered; a presser plate hinged adjacent one side of the form, means for securing a covering fabric along the outer edge of the form, the ends thereof and the ends of the presser plate; and means for forcing a chair arm downwardly into contact with the fabric overlying the form.

4. In a machine for producing over-stuffed furniture elements, the combination of a form trough-like in shape and having a contour such as is desired to be imparted to the upper portion of the finished furniture element; a presser plate hinged at its lower edge adjacent one side of the form; means for securing the desired covering fabric along the outer edge of the form, the ends thereof and the ends of the presser plate; and means for holding the presser plate in an inclined position away from the form, said means permitting the presser plate to move inwardly when the furniture element is forced downwardly into contact with the covering or with the filling which may be imposed thereon.

5. In a machine for producing over-stuffed furniture elements, the combination of a pair of forms standing in spaced relation to each other, said forms being trough-like in shape and having a contour such as is desired to be imparted to the upper portion of the finished furniture element; a presser plate hinged at its lower edge adjacent each of the forms and adapted to be swung inwardly at their upper edges toward each other; and means connecting said plates, said means permitting the presser plates to move inwardly toward their respective forms when the furniture element is forced downwardly into contact with the covering overlying the form or with the filling which may be imposed upon said covering.

6. In a machine for producing over-stuffed furniture elements, the combination of a pair of forms standing in spaced relation, said forms being trough-like in shape and having a contour such as is desired to be imparted to the upper portions of the finished furniture elements; a presser plate hinged adjacent the inner edge of each of said forms; means for securing the desired covering fabric along the outer edge of each form, the ends thereof and the ends of the presser plates; a pair of links pivotally connected to each other at their adjacent ends and likewise connected at their outer ends to the respective presser plates; and a stop element coacting with the inner ends of links when the same are moved from their straightened position and the presser plates brought to the desired inclination away from their respective forms.

7. In a machine for producing over-stuffed furniture element, the combination of a support; a trough-like element mounted thereon, said trough being provided at one side with a flexible upstanding element; a presser plate hinged to the support adjacent said flexible trough portion, said plate and flexible portion standing in overlapping relation at the lower edge of the presser plate; and means for securing the desired covering fabric along the outer edge of the trough, the ends thereof and the ends of the presser plate.

8. In a machine for producing over-stuffed chairs, the combination of a pair of forms adapted to produce the desired contour to the upper portions of the arms of a chair, said forms standing in spaced relation to each other; a hinged presser plate associated with the inner portion of each of said forms and extending upwardly therefrom; a back contouring member mounted for swinging movement, said member standing to the rear of said arm contouring forms; and means for rocking said back contouring member.

9. In a machine for producing over-stuffed chairs, the combination of a pair of forms adapted to produce the desired contour to the upper portions of the arms of a chair, said forms standing in spaced relation to each other; a hinged presser plate associated with the inner portion of each of said forms and extending upwardly therefrom; a back contouring member mounted for swinging movement, said member standing to the rear of said arm contouring forms; means for rocking said back contouring member; and a pair of wings extending outwardly at substantially right angles to the outer face of said back contouring member.

10. In a machine for producing over-stuffed chairs, the combination of a pair of forms adapted to produce the desired contour to the upper portions of the arms of a chair, said forms standing in spaced relation to each other; a hinged presser plate associated with each of said forms and located adjacent the inner edge thereof and extending upwardly therefrom; a back contouring member pivotally supported at its lower end, said member standing immediately adjacent the rear ends of the arm contouring forms, said back contouring member being provided at its lower portion with an arcuate shaped member; a pair of wings extending outwardly at right angles to the rear face of said back contouring member and adjacent the upper end thereof; and means for rocking said back contouring member.

11. In a machine for upholstering chairs, the combination of a suitable support; a back contouring member mounted for swinging movement thereon, said member at its outer lower portion being provided with a trough-shaped portion curved and contoured

to conform with the top of the back of the chair which is to be upholstered; a pair of wings extending outwardly to the rear of said back contouring member at the upper portion thereof; and means for rocking said back.

5 In testimony whereof I have signed my name to this specification.
